E. S. AKER

SHOCK ABSORBER

Filed Nov. 17, 1922

INVENTOR.

Evander S. Aker,

BY

Fraunfeld and Richards,
ATTORNEYS.

UNITED STATES PATENT OFFICE.

EVENDER S. AKER, OF GOSHEN, NEW YORK.

SHOCK ABSORBER.

Application filed November 17, 1922. Serial No. 601,450.

To all whom it may concern:

Be it known that I, EVENDER S. AKER, a citizen of the United States, residing at Goshen, in the county of Orange and State 5 of New York, have invented certain new and useful Improvements in Shock Absorbers; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates, generally, to improvements in shock-absorbers for vehicles, and the invention has for its principal object to provide an improved shock-absorber comprising a cylinder containing a suitable 20 fluid, and a piston, said piston having a normally open by-pass valve, means being provided to actuate the by-pass valve to gradually close the same as the piston moves downwardly in the cylinder from its normal 25 initial position whereby the flow of fluid from one side of the piston to the other is gradually stopped so that an increasing resistance is opposed to the piston movement as it approaches the downward 30 limit of its stroke. A further object of the invention is to provide an arrangement of piston in the cylinder whereby the former is capable of an upward rebound stroke beyond its normal initial position, means also 35 being provided to actuate the by-pass valve to close the same as the piston approaches the upward limit of such rebound stroke, whereby the flow of fluid through the piston ports is checked to oppose an increasing 40 resistance to such upward rebound stroke. Another object of the invention is to provide in connection with the upper outer 45 end of the piston stem an air cylinder or chamber synchronously movable with the fluid piston to cooperate with a fixed piston attached to the upper end of the fluid cylinder whereby on the downward stroke of said fluid piston the air within said air cylinder or chamber is compressed so that additional 50 resistance is offered to the downward stroke of said fluid piston while at the same time the compression of the air produces a more or less elastic cushioning effect relative to the operation of the shock absorber as a whole.

55 Other objects of this invention, not at this

time more particularly enumerated, will be clearly understood from the following detailed description of the same.

With the various objects of this invention 60 in view, the same consists, primarily, in the novel construction and arrangement of shock-absorber for vehicles hereinafter set forth; and the invention consists, furthermore, in the novel arrangements and combinations of the various devices and parts, as well as in the details of the construction of the same, all of which will be hereinafter more fully described, and then finally embodied in the claims appended to this speci- 65

70

The invention is clearly illustrated in the accompanying drawings, in which:—

Figure 1 is a longitudinal vertical section illustrating the novel shock-absorber made 75 according to and embodying the principles of this invention, the operative parts being shown in their normal initial positions; Figure 2 is a horizontal cross section, taken on line 2—2 in Figure 1; Figure 3 is a longitudinal vertical section illustrating the relation of the operative parts as the fluid piston approaches the limit of its downward stroke; Figure 4 is a horizontal section, taken on line 4—4 in said Figure 3; and Figure 5 80 is a fragmentary detail longitudinal vertical section taken in a plane at right angles to the sectional plane of Figure 1.

Similar characters of reference are employed in all of the hereinabove described 85 views, to indicate corresponding parts.

Referring now to said drawings, the reference character 6 indicates a fluid containing cylinder closed at its bottom end, and having its upper end closed by a detachable cylinder 95 head or cap 7. Said cylinder head or cap is provided with a central stuffing-box 8, through which extends the tubular stem 9 of a piston 10 movable in said cylinder 6. A gland 11 fits slidingly into the upper end of the stuffing-box 8 to engage and hold the packing 12 around the piston stem 9. The upper free end of said piston stem 9 is provided with a perforate ear or lug 13. Suitably secured in connection with the upper free end of said piston stem 9 and the ear or lug 13 is the upper closed end 14 of an air cylinder 15, the latter being of slightly larger internal diameter than the external diameter of the fluid containing cylinder 6, 100 so that the lower open end of the same may pass telescopically over said cylinder 6. The 105

110

reference character 16 indicates a fixed piston member which is engaged over the stuffing-box 8, and securely clamped or fastened between a shoulder 17 on the upper side of the cylinder head or cap 7 at the base of said stuffing-box and a clamp nut 18, the upper end of said stuffing-box 8 being externally threaded to receive said clamp-nut 18. The periphery of said fixed piston member 16 engages the internal walls of said air cylinder 15 as shown in Figures 1 and 3 of the drawings. Arranged about the piston stem 9 intermediate the upper end wall 14 of said air cylinder 15 and the exterior end of the gland 11 is a compression spring 19 which holds said gland in operative relation to the packing 12.

Secured to the bottom end wall of said fluid containing cylinder 6, in a central longitudinal position so as to extend upwardly through the interior of said cylinder, with its upper end slidably or telescopically engaged by the lower end of the tubular stem 9 of said piston 10, is a tubular guide-member 20. Said piston 10 occupies a normal initial position within the cylinder 6 spacing the same downwardly from the upper end of the said cylinder for a distance approximating about one-third of the total length of said cylinder. Said piston is provided in its body with one or more vertical valve ports or openings 21. Registered against the bottom of said piston 10 is a valve disc 22, also provided with one or more valve ports or openings 23 which align themselves with the valve ports or openings of said piston 10 when the latter occupies its normal initial position in the cylinder. Said valve disc 22 is held in operative association with or attachment to the bottom of said piston 10, by means of studs 24 which are fixed to said piston 10 to project downwardly therefrom through concentric or curvilinear slots 25 provided in the valve disc 22, the free ends of said studs 24 having enlarged heads 26 for retaining the valve disc in place. As thus mounted and supported relative to the bottom of the piston 10, said valve disc 22 is free to turn about the axis of the piston and its stem. The means for producing operative movement of said valve disc 22 consists of cam-grooves 27 provided in the walls of said guide-member into which extend lugs 28 formed to project inwardly from the inner annular periphery of the valve disc 22. Said cam-grooves 27 possess a downwardly extending spirally formed portion 27' extending from the initial position of the piston downwardly toward the bottom of the cylinder 6, and an upwardly extending spirally formed portion 27'' of sharper pitch extending from the initial position of the piston upwardly toward the top of the cylinder 6.

When the piston 10 occupies its normal initial position intermediate the ends of the cylinder 6, the lugs 28 of the valve disc 22 engage neutral portions of the cam grooves 27 whereby the valve disc 22 is normally positioned so as to aline its ports 23 with the ports 21 of the piston 10. When the pressure or force of a shock is transmitted to the piston stem 9 tending to move the piston 10 downwardly in the cylinder 6, the fluid beneath the piston will be caused to flow upwardly through said alined ports 23 and 21 as the piston descends in the cylinder, but since in moving downward the piston carries the valve disc lugs 28 downwardly into the spiral cam portions 27', the valve disc 22 is gradually rotated during the descent of the piston, so that the valve ports 23 are gradually moved out of alinement with the valve ports 21 thereby gradually closing the latter against the upward flow of fluid, and consequently opposing to the descent of the piston 10 a constantly increasing pressure due to the gradual compression of the fluid between the piston and the bottom of the cylinder as the free flow of such fluid past the piston is checked. As a consequence of this action shocks are absorbed and gradually reduced in a very efficient manner as will be understood. Upon rebound after the transmission of a shock to the absorber, the piston 10 will move upward in the cylinder 6, which movement is accompanied by a reverse rotation of the valve disc 22 tending to again open the piston valve ports 21 to the return flow of fluid to the under side of the piston. If, when the piston reaches normal initial position, the rebound reaction is strong enough to move the piston upwardly in the cylinder 6 beyond its said normal initial position, then the lugs 28 of the valve disc 22 are carried into operative engagement with the portions 27'' of the cam grooves, whereby the valve disc is turned to close the piston ports 21 as said piston approaches the upper end of the cylinder, and thereby opposes the downward flow of fluid past the piston resulting in gradually compressing the fluid to produce an increasing resistance to such continuous upward movement of the piston. This action tends to cushion or reduce the violence of rebound reaction of the parts served by the shock-absorber and tends to bring said parts easily and quickly back to the normal status quo.

From the above description it will be apparent that my present invention provides a very simply constructed shock-absorber which will operate efficiently to absorb both original shocks and violent rebound reaction after absorption of the force of said original shock, the novel piston valve mechanism being arranged and constructed to operate gradually so as not to produce

a too abrupt check of the piston movement or a too sudden compression of the fluid against which the piston operates. The operation and purpose of the other features 5 of my invention, as, e. g., the air cylinder and fixed piston cooperating therewith will be understood without further reiteration.

I am aware that some changes may be made in the arrangements and combinations 10 of the various devices and parts, as well as in the details of the construction of the same, without departing from the scope of my present invention as set forth in the foregoing specification, and as defined in 15 the appended claims. Hence, I do not limit my invention to the exact arrangements and combinations of the several devices and parts as described in said foregoing specification, nor do I confine myself to the exact 20 details of the construction of said parts as illustrated in the accompanying drawings.

I claim:-

1. A shock-absorber comprising a fixed cylinder adapted to contain a fluid, a movable piston therein, a piston stem projecting exteriorly from the upper end of said cylinder, said piston having a valve port, a movable valve-disc having a port normally alined with said piston valve-port, 25 means cooperating with said valve-disc for moving the same to close said piston valve-port as the piston makes its operative descent in said cylinder, a movable air cylinder fixed to the exterior end of said piston 30 stem, the lower open end of which is arranged telescopically over the upper end of said fixed cylinder, and a fixed piston member connected with the upper end of said fixed cylinder to fit and cooperate with said 35 movable cylinder.

2. A shock-absorber comprising a fixed cylinder adapted to contain a fluid, a movable piston therein, a movable piston stem projecting exteriorly from the upper end 45 of said cylinder, said movable piston being normally initially positioned intermediate the upper and lower ends of said cylinder, said piston having a valve-port, a movable valve-disc having a port normally alined 50 with said piston valve-port, means cooperating with said valve for moving the same to gradually close said piston valve-port as the piston descends from normal initial position toward the lower end of said 55 cylinder and also for moving the same to close said piston valve-port as the piston ascends from normal initial position toward the upper end of said cylinder, a mov-

able air cylinder fixed to the exterior end of said piston stem, the lower open end of which is arranged telescopically over the upper end of said fixed cylinder, and a fixed piston member connected with the upper end of said fixed cylinder to fit and cooperate with said movable cylinder. 60

3. A shock absorber comprising a cylinder, a piston therein, a tubular piston stem projecting exteriorly from the upper end of said cylinder, said piston having a valve-port, a movable valve disc mounted on the under side of said piston to rotate about the vertical axis of said piston and its stem, 70 said valve disc having a port normally alined with said piston valve-port, a guide member extending upwardly in central longitudinal 75 position from the bottom of said piston, over which said piston and its stem and said valve disc are slidably engaged, cam-grooves in said guide-member, and means on said valve-disc for cooperating with said cam-grooves for the purposes described. 80

4. A shock-absorber comprising a cylinder, a piston therein having a valve port, said piston being normally initially positioned intermediate the upper and lower ends of said cylinder, a tubular piston stem projecting exteriorly from the upper end of said cylinder, a movable valve-disc mounted on the under side of said piston to rotate about the vertical axis of said piston and its stem, 85 said valve-disc having a port normally alined with said piston valve-port, a guide-member extending upwardly in central longitudinal position from the bottom of said piston, over which said piston and its 90 stem and said valve-disc are slidably engaged, cam-grooves in said guide-member, said cam-grooves having spirally curved portions extending downwardly from the normal initial position of said piston toward the lower end of said cylinder, said cam-grooves having additional spirally curved 95 portions extending from the normal initial position of said piston upwardly from the normal initial position of said piston toward the upper end of said cylinder, and means on said valve-disc for cooperating with said cam-grooves for the purposes described. 100

In testimony that I claim the invention 110 set forth above I have hereunto set my hand this 15th day of November, 1922.
